UNITED STATES PATENT OFFICE.

GUSTAVE A. SPAETH, OF COLUMBUS, OHIO.

COLLAR-BUTTON.

SPECIFICATION forming part of Letters Patent No. 765,862, dated July 26, 1904.

Application filed November 6, 1903. Serial No. 180,108. (No model.)

To all whom it may concern:

Be it known that I, GUSTAVE A. SPAETH, a citizen of the United States, residing at Columbus, in the county of Franklin and State 5 of Ohio, have invented certain new and useful Improvements in Collar-Buttons; and I do hereby declare the following to be a full, clear, and exact description of the invention, such as will enable others skilled in the art to which 10 it appertains to make and use the same.

This invention relates to collar-buttons; and it consists of an attachment for opening out the buttonhole, as hereinafter fully described and claimed.

15 In the drawings, Figure 1 is a longitudinal section through a collar-button, showing the attachment applied to it. Fig. 2 is a front view of the collar-button and its attachment. Fig. 3 is a perspective view showing the collar-button and its attachment and a portion of a collar. Fig. 4 is a detail view of the button and the blade shown separate from each other.

20 A is a collar-button of any approved form 25 provided with a guide-hole *b*, formed longitudinally in its head.

B is the opening attachment, which consists 30 of a tapering blade having a central projection *c* at its rear end for engaging with the hole *b* and two wings *d*, which engage with the head of the collar-button. The two wings are formed so as to fit the head of the button 35 snugly, and they may be spring-wings, so as to insure a close contact, but this is not essential; but the wings should taper outwardly

to conform with the outline of the head and fit tightly to it. The blade is preferably thrust about half-way through the buttonhole, and its rear end is then placed in engagement with the head of the collar-button, and the 40 collar is then forced over the blade into engagement with the shank of the collar-button.

What I claim is—

1. The combination, with a collar-button having an axial hole in its head, of a tapering 45 opening-blade for the buttonhole provided with an axial projection on its larger end for engaging with the said hole in the collar-button and having also side wings which straddle the head of the said collar-button. 50

2. The combination, with a collar-button having a longitudinal hole in its head, of a tapering blade provided with a central projection at its rear end for engaging with the said hole, and having also two spring-wings 55 which engage with the said head.

3. The combination, with a collar-button provided with a head having a hole in it arranged axially in line with its shank, of a tapering blade provided with side wings on its 60 larger end which straddle the said head and having a projection between the said wings for engaging with the said hole.

In testimony whereof I affix my signature in presence of two witnesses.

GUSTAVE A. SPAETH.
